UNITED STATES PATENT OFFICE

ANTON YURKOVITCH, OF PITTSBURGH, PENNSYLVANIA

CLOTHES STICK

Application filed February 4, 1931. Serial No. 513,281.

This invention relates to a clothes stick or to a similar or analogous article of manufacture adapted for similar purpose.

Known devices of this nature are either unduly complicated or expensive or they are insufficiently strong or awkward to handle. They are further inefficient in that they do not perform and function completely, but allow a portion of the clothes to slip from the stick. This will be understood when it is realized that the weight of clothes which have been washed are heavy and oftentimes slippery due to adhering soap or the like. This doubly tends to cause the clothes to slip from the clothes stick, thus increasing the work involved and the time required for completing the operations. Since the water used is generally quite hot, it is both impractical and undesirable to carry out these procedures manually.

I have, therefore, invented a clothes stick designed to obviate the above noted disadvantages and at the same time to present additional advantages peculiar to its own construction.

Another object of the invention is to provide a sturdy clothes stick of simple, yet efficient construction which will enable the indicated task to be performed with the minimum time and effort.

A further object is to provide a clothes stick which may either be made entirely in one piece, in which case the stick is preferably made all of wood, or of two pieces, in which case, the head portion is made of metal and the handle of wood.

Other and further objects and advantages will be understood by those skilled in this particular field.

In the accompanying drawings:

Figure 1 shows a face view of a clothes stick made according to one form of the present invention;

Fig. 2 shows an edge view of the clothes stick of Fig. 1;

Fig. 3 shows a view similar to Fig. 1, but partly in section, of a modified form of the invention;

Fig. 4 is a view partly in section at right angles to Fig. 3; and

Fig. 5 is a view substantially similar to Fig. 4, but embodying the form of Figs. 1 and 2 in certain respects.

Similar numerals refer to similar parts throughout the several views.

Referring first to Figs. 1 and 2, I have shown a clothes stick which is preferably paddle shaped in general configuration and which is constructed throughout of wood and which is made in one piece. This form of the invention embodies a head or blade portion 10 and a handle portion 11, the material between the head and handle being suitably shaped and contoured so as to provide the shoulders 12, looking at Fig. 1, and the tapered portion 13, as seen from Fig. 2. The head 10 in this case is made of substantial thickness so that the device will have the proper strength and surface requirements. The wood may, of course, be any suitable or known kind, and the nature of the material per se is not a part of the present invention. Formed suitably on the head portion 10 are the ribs or corrugations 14 which increase the surface of the head and at the same time offer frictional resistance to the clothes so as to enhance the effectiveness of the stick as a whole.

In Figs. 3 and 4, I have shown a modification of the invention which is different in at least two respects. In this case, the head member 15 is formed of a suitable metal which may be cast, for example, and the head has a neck portion 16 terminating in a collar or reinforcement 17, members 16 and 17 being

hollow down nearly as far as about the shoulders 18, so that a socket is formed for a purpose to be hereinafter noted. The head of this modification is provided with transverse

ribs or corrugations 19 instead of the longitudinal ones of Figs. 1 and 2. The shape of the ribs or corrugations is not limited, of course, to the shape shown, which is intended

to be purely illustrative of a simple and effective form thereof and wherein the ribs or corrugations taper relatively sharply, but

have rounded extremities so as to present no sharp or abrupt surfaces to the clothes, thereby eliminating any possibility of cutting or tearing them thereon. So are also all other

surfaces of the stick which contact with the clothes. As has been stated, the head member of Figs. 3 and 4 is of metal and the neck portion 16 has a suitable aperture 20 registering with an aperture 21 in the neck or reduced portion 22 of wooden handle member 23, the reduced portion being received in the socket of the head in such manner as to register the holes aforesaid whereupon a suitable fastening or securing element 24 is inserted therein to hold the members in the assembled position. Where the head is made of metal, as in Figs. 3 and 4, the added strength of the material permits the head 15 to be formed thinner and this will be noted by a comparison of Figs. 2 and 4 which illustrate the differences in the wooden and metal heads respectively. The shoulders 18 and tapered portion 25 are similarly provided as 20 in the form shown in Figs. 1 and 2.

In Fig. 5, I have shown the same construction essentially as that of Figs. 3 and 4, but the ribs or corrugations 26 are longitudinally disposed with respect to the head 27 in the 25 general manner of Figs. 1 and 2 instead of transversely, but it is apparent that any of the above noted modifications may be provided with either the longitudinal or the transverse ribs or corrugations and in fact, 30 if I so desire, I may dispose the same at some other angle to suit any given circumstances. In the modifications of Figs. 3, 4 and 5, the invention is also shown in the preferred spatu- 35 late form, although not limited thereto.

In use, whatever be the precise form which the invention takes, the clothes stick is dipped or immersed into the tub or the like containing the clothes until the shoulders are submerged under the same and then the stick is 40 simultaneously twisted around and slowly withdrawn so that the clothes wind themselves about the head and are accordingly held by the shoulders and/or the ribs or corrugations. They may be allowed to drain, 45 if desired, a suitable time and then they may be simply disengaged from the stick as will be understood.

It is clear that the above is indicative of 50 certain forms of the device which may be used, but that I am not limited only thereto. For example, I may vary the shape or length of the stick or its proportions and likewise the materials from which it is made. While 55 I prefer the wood and metal and wood constructions which have been shown I may, of course, utilize other compositions natural or synthetic without departing from the spirit and scope of the invention. In practice the 60 stick may be of about 30 inches in length and of proportionate other dimensions, but may be made larger or smaller as circumstances may require. The invention is adapted not only to the said uses, but also to commercial 65 uses in laundries, hospitals, etc.

What I claim as new and desire to secure by Letters Patent is:

A clothes stick comprising a head and a handle, the head being paddle shaped and composed of metal, said head having a terminal socket and spaced corrugations extending over its flat surfaces, and said handle having an end portion fitted into said socket.

In testimony whereof, I have hereunto subscribed my name this 31st day of January, 75 1931.

ANTON YURKOVITCH.
